(57) **CLAIM**

The ornamental design for a navigation device as shown and described.

DESCRIPTION

This invention was made with government support under contract number OTA 19 01C 001 awarded by the United States Space Force. The government has certain rights in the invention.

FIG. 1 is a top, front, and side perspective view of a navigation device showing our new design;

FIG. 2 is a top, rear, and side perspective view thereof;

FIG. 3 is a front view thereof;

FIG. 4 is rear view thereof;

FIG. 5 is a left-side view thereof;

FIG. 6 is a right-side view thereof;

FIG. 7 is a top view thereof; and,

FIG. 8 is a bottom view thereof.

Features illustrated in broken lines form no part of the claimed design.
